Primary Examiner — Katrina A Betton(74) *Attorney, Agent, or Firm* — Steven M. Koehler; Westman, Champlin & Koehler, P.A.**CLAIM**

The ornamental design for a wall assembly and canopy, as shown and described.

DESCRIPTION

FIG. 1 is a perspective view of the wall assembly and canopy.

FIG. 2 is a top plan view of the wall assembly and canopy.

FIG. 3 is a right side view of the wall assembly and canopy; and,

FIG. 4 is a left side view of the wall assembly and canopy. The broken lines immediately adjacent the shaded areas having alternating long and short dashes represent the bounds of the claimed design where all other broken lines are directed to environment and are for illustrative purposes only.
